UNITED STATES PATENT OFFICE.

HIRAM L. BROWN, OF VISTULA, ASSIGNOR OF ONE-HALF TO GEORGE N.
THOMAS AND ELI ALBRIGHT, OF GOSHEN, INDIANA.

PISTON.

SPECIFICATION forming part of Letters Patent No. 311,806, dated February 3, 1885.

Application filed July 25, 1884. (No model.)

To all whom it may concern:

Be it known that I, HIRAM L. BROWN, a citizen of the United States, and a resident of Vistula, in the county of Elkhart and State of Indiana, have invented certain new and useful Improvements in Pistons; and I do hereby declare that the following is a full, clear, and exact description of the invention, which will enable others skilled in the art to which it applies to make and use the same, reference being had to the accompanying drawings, which form a part of this specification, and in which—

Figure 1 is a top view of my improved piston for hydraulic presses. Fig. 2 is a vertical section of the same, and Fig. 3 is a perspective view of the several parts constituting the piston.

Similar letters of reference indicate corresponding parts in all the figures.

My invention has relation to that class of pistons in which the packing may be tightened around the periphery of the piston; and it consists in the improved construction and combination of parts of a piston especially adapted for hydraulic presses in which the packing may be tightened around the entire periphery by turning a cam-disk, as herein-after more fully described and claimed.

In the accompanying drawings, the letter A indicates the body of the piston, from the center of which projects a screw-threaded bolt, B, and a cup-shaped packing-disk, of leather or similar material, (shown at C,) fits with its perforated center upon the said bolt, and has a flange, D, adapted to bear against the side of the cylinder in which the piston travels. A disk, E, having an annular recess, F, at the edge of its face, and having a number of radiating recesses, G, forming sector-shaped blocks H, upon the face of the disk, fits with its center upon the bolt fitting within the cup-shaped leather packing. A number of T-shaped blocks, I, fit and slide with their inwardly-pointing arms J in the radiating recesses, the said arms being of the same thickness as the depth of the recesses, while the outer sides of the segmental cross-heads K of the blocks bear against the inner sides of the flange of the packing-disk, and the said cross-heads are thicker than the arms, and are provided upon the inwardly-facing shoulders

formed by them with ratchet or wedge-shaped projections L.

M is a disk having a central perforation fitting upon the central bolt, and the said disk has a number of ratchet-teeth or cam projections, N, upon its edge corresponding in number and location to the projections upon the T-shaped blocks, and bearing with their outer edges against the said projections, and the disk has a polygonal nut or projection, O, at its center for the attachment of a wrench for turning the disk, and a nut, P, fits upon the upper screw-threaded end of the central bolt and serves to clamp the cam-disk in its adjusted position. It will be seen that by turning the cam-disk so as to bring the ratchet-teeth to bear against the projections upon the blocks the said blocks may be forced outward so as to bear against the flange of the packing-disk and force the said flange against the side of the cylinder in which the piston fits and travels, and thus cause it to fit tighter, or by reversing the disk the packing may be loosened, causing the piston to travel more freely.

Having thus described my invention, I claim and desire to secure by Letters Patent of the United States—

The combination of a piston-body, a packing-disk having an overturned flange, a screw-threaded bolt axial to the piston-body and projecting from its face, a disk having an annular recess at the edge of its face and having radiating grooves or recesses, T-shaped blocks having arms sliding in the radiating recesses, and having segmental cross-heads formed with inwardly-facing shoulders having ratchet or wedge shaped projections, a disk turning upon the axial bolt having ratchet-teeth or cam projections corresponding in number and location to the projections upon the blocks and having a central nut, and a clamping-nut fitting upon the threaded central bolt and bearing against the nut of the disk, as and for the purpose shown and set forth.

In testimony that I claim the foregoing as my own I have hereunto affixed my signature in presence of two witnesses.

HIRAM L. BROWN.

Witnesses:

CHARLES H. BROOKS,
PHILIP M. HENKEL.
